US00D426945S

United States Patent [19]**Edwards****Patent Number: Des. 426,945****Date of Patent: ** Jun. 27, 2000**

[54] **COMBINED SHOE BOTTOM AND PERIPHERY**

[75] Inventor: **D'Wayne Edwards**, Torrance, Calif.

[73] Assignee: **Skechers U.S.A., Inc.**, Manhattan Beach, Calif.

[**] Term: **14 Years**

[21] Appl. No.: **29/103,955**

[22] Filed: **Apr. 23, 1999**

[51] LOC (7) Cl. **02-04**

[52] U.S. Cl. **D2/951; D2/957; D2/960**

[58] **Field of Search** .... D2/896, 897, 902, D2/906, 908, 909, 914, 916, 919, 946-962, 964, 977; 36/3 B, 11.5, 12-15, 25 R, 28, 32 R, 44, 59 C, 66, 75 R, 76 R, 85, 101, 103, 104, 106, 113-115, 124, 126, 127-130

[57]

CLAIM

The ornamental design for a combined shoe bottom and periphery, as shown and described.

DESCRIPTION

FIG. 1 is a perspective view of the right, front and bottom of a combined shoe bottom and periphery showing my new design;

FIG. 2 is a bottom plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The broken line showing of the shoe upper in FIG. 1 is for illustrative purposes only; said broken lines and the unshaded portion in FIG. 5 forming no part of the claimed design.
